UNITED STATES PATENT OFFICE

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY

SEWING MACHINE

Application filed January 28, 1928. Serial No. 250,111.

This invention relates to sewing machines of the cylinder-bed chain-stitch type and has for an object to provide a sewing machine with simplified and compact feeding, looper-actuating and looper-thread controlling mechanism particularly adapted to be housed in the restricted space within the cylinder-bed.

The machine is provided with a main-shaft 10 extending transversely of the sewing machine standard, in line with and extending into the cylinder-bed and preferably terminating at a bearing-lug disposed about midway the length of such bed. The direction of feed is 15 across the cylinder and the feed-dog is carried by an inverted U-shaped yoke, the legs of which are pivotally carried by crank-arms fixed to a feed-lift rock-shaft extending the full length of the cylinder and actuated by a 20 link- and eccentric-connection with the main-shaft. The feed-and-return motion of the feed-dog is derived from a short rock-shaft journaled in the bearing-lug which supports the front end of the main-shaft. This rock- 25 shaft carries a slotted arm which extends horizontally rearwardly across the cylinder. A bell-crank lever loosely journaled on the feed-lift rock-shaft has a horizontal slotted arm extending forwardly across the cylinder, 30 close to the first mentioned slotted arm. A connecting-pin is adjustably mounted in the slotted bell-crank lever arm and extends into the other slotted arm. The bell-crank lever has an upstanding slotted arm which receives 35 a pin on the feed-dog carrying yoke to rock the latter and thus give the feed-dog its feed-and-return components of motion.

The looper-mechanism comprises a sliding and rocking looper-shaft extending length- 40 wise of the cylinder below the main-shaft. Rocking movements of the looper-shaft are derived from a long eccentric on the main-shaft, which eccentric is slidably embraced by a forked arm fixed to the looper-shaft. Slid- 45 ing movement of the looper-shaft is derived from a bell-crank and link connection with the needle-bar operating rock-shaft, which, in turn, is actuated by a crank-and-pitman connection with the main-shaft.

60 The looper-thread controlling-mechanism

comprises a crank-and-link take-up device disposed within and preferably crosswise of the cylinder, at the end of the main-shaft, and between the latter and the two slotted arms of the feed-and-return actuating mechanism. The anchor-link of the take-up is loosely carried by the feed-lift rock-shaft.

The invention will be better understood by referring to the accompanying drawings, in which Fig. 1 is a side view, in section, of the entire sewing machine. Fig. 2 is a horizontal section through the cylinder-bed and standard. Fig. 3 is a section on the line 3—3, Fig. 2. Fig. 4 is a disassembled perspective view of the feed-dog carrying-yoke and its actuating bell-crank lever. Fig. 5 is a perspective view of the looper-thread controller actuating-cranks. Fig. 6 is a section on the line 6—6, Fig. 1. Fig. 7 is an end view of the mechanism within the cylinder-bed. Figs. 8, 9 and 10 are, respectively, sectional views on the lines 8—8, 9—9 and 10—10, Fig. 2, and Fig. 11 is a perspective view of the looper-thread controlling-lever with the thread-carrying arms thereof removed.

In the preferred embodiment of the invention illustrated, 1 represents the standard of the sewing machine and 2 the overhanging bracket-arm which terminates in the head 3. Projecting horizontally from the standard 1, below the arm 2, is the cylinder-bed 4. Journaled in bearings 5, 6 and 7 is the main-shaft 8, which extends within and lengthwise of the cylinder-bed 4, and terminates at the point 9, Fig. 2, about mid-way the length of the cylinder-bed. The main-shaft 8 is formed with the crank 10 which is connected by the pitman 11 to the ball 12 on one arm 13 of a double crank fixed to the needle-bar operating rock-shaft 14, which, at its forward end, has the usual crank 15 and link-connection 16 with the reciprocating needle-bar 17 carrying the eye-pointed needles 18. The presser-foot 19 is carried, as usual, by the downwardly spring-pressed presser-bar 20.

Cooperating with the presser-foot 19 to feed the work across the cylinder 4 is the four-motion feed-dog 21 which is mounted on the inverted U-shaped feed-bar 22 having at the ends of its downwardly extending legs

23 the aligned bearing-pins 24 which are sustained by the feed-lifting arms 25 fixed to the feed-lift rock-shaft 26. The feed-lift rock-shaft 26 extends the full length of the cylinder-bed 4 and into the standard 1 where it has fixed thereto, Fig. 6, a crank-arm 27 pivotally connected at 28 to the eccentric-strap member 29 embracing the feed-lift eccentric 30 on the main-shaft 8.

10 The bearing-lug 5 has journaled therein the short feed-advancing rock-shaft 31 to the rear end of which, Fig. 9, is fixed the crank-arm 32 which is pivotally connected at 33 to the pitman 34 which is actuated by the eccentric 35 on the main-shaft 8. Fixed to the forward end of the rock-shaft 31 is a horizontally disposed crank-arm 36 formed in its side face with a slot 37 which receives the block 38 on the pin 39. The pin 39 is adjustably secured to the horizontally slotted arm 40, the split hub 41 of which is clamped to the sleeved bearing-hub 42 of a rocker-arm 43 formed in its side face with a slot 44. The slot 44 receives the block 45 on the pin 46 which is fixed to the feed-bar 22. The hub 42 of the arm 43 is free to turn upon and relative to the rock-shaft 26, and the arms 40 and 43 which are clamped together by the split-hub 41, constitute a bell-crank lever for transmitting the up-and-down motion of the pin 39 to the pin 46 to which is imparted a feed-and-return motion.

15 The loopers 47, which cooperate with the needles 18, are secured to the looper-carrier 38 which is fixed to the forward end of the rocking and sliding looper-shaft 49 journaled in the cylinder-bed below the main-shaft 8. The sliding movement of the looper-shaft 49 which imparts the loop-seizing and -shedding movements to the loopers, is derived through a train of connections with the arm 50 of the double-armed lever 13, 50 fixed to the needle-bar operating rock-shaft 14. The arm 50 carries a ball 51 to which is connected the upper end of a link 52 connected at its lower end to the ball 53 on the horizontal arm 54 of a bell-crank lever 54, 55 fulcrumed on the shaft 56 in the standard 1. The bell-crank lever arm 55 is forked at its upper end 20 to embrace the split-block 57 which, in turn, embraces the ball-ended arm 58 fixed to the looper-shaft 49.

25 The needle-avoiding movements of the loopers are produced by a rocking motion of the looper-shaft 49 which is derived from the eccentric 59 in the main-shaft 8. The eccentric 59 is embraced by the split-block 60 the flat sides of which are embraced by the forked upper end of the arm 61, fixed to the looper-shaft 49. The split-block 60 is long enough to accommodate the movements of the arm 61 with the shaft 49 lengthwise of the cylinder-bed.

30 The looper-thread controlling mechanism 65 comprises a crank and link take-up mounted

within and crosswise of the cylinder-bed at the end of the main-shaft 8. Fixed to the main-shaft is the circular head 62 carrying the crank-pin 63 which is embraced by one end of the lever-arm 64 fulcrumed at 65 to one end of the anchor-link 66 journaled freely on the rock-shaft 26. The lever 64 is provided with spaced sockets 64' in which are fitted the thread-arms 67 having in their free ends the thread-eyes 68. Between the arms 67 is mounted on the bearing-lug 5 the fixed thread-guide 69. At the rear of the rearwardly disposed take-up arm 67 is mounted a second fixed thread-guide 70. When the loopers are fully advanced, the movable thread-eyes 68 are in substantial alignment with the thread-eyes in the fixed guides 69 and 70. As the loopers retract, the movement of the thread-eyes 68, toward their dotted line position, Fig. 10, takes up the slack looper-thread. The return movement of the thread-eyes 68 to their full line position, Fig. 10, gives up thread to the loopers in their movement to the end of their advancing stroke.

35 The split hub 41 may be loosened to permit the lever 43 and its sleeved hub to be rocked relative thereto to adjust the feed-dog to a central working position in the feed-slots 71 of the throat-plate 72.

Having thus set forth the nature of the invention, what I claim herein is:—

1. Feeding mechanism for sewing machines comprising a cylinder-bed, an inverted U-shaped feed-bar, feed-lift and feed-advance rock-shafts, spaced arms on the feed-lift rock-shaft pivotally connected to the ends of the legs of said feed-bar, a lever fulcrumed coaxially with said feed-lift rock-shaft, a feed-advance connection between said lever and said feed-bar, and a feed adjusting connection between said feed-advance rock-shaft and said lever.

2. In a sewing machine, a cylinder-bed, a feed-dog, a feed-bar, feed-lift mechanism connected to said feed-bar, a feed-advance rock-shaft journaled in and lengthwise of said cylinder-bed at one side of the latter, a slotted arm carried by said feed-advance rock-shaft and extending crosswise of said cylinder-bed, a bell-crank lever fulcrumed at the other side of said cylinder-bed and having one of its arms slotted and extending toward the feed-advance rock-shaft alongside the first mentioned slotted arm, an operative connection between the other arm of the bell-crank lever and the feed-bar, and a feed-adjusting pin adjustably secured to one of said slotted arms and extending into the slot in the other slotted arm.

3. In a sewing machine, a cylinder-bed, feed-advance and feed-lift rock-shafts journaled in said bed, a slotted arm on said feed-advance rock-shaft extending toward said feed-lift rock-shaft, a lever fulcrumed coaxially with said feed-lift rock-shaft and hav-

ing one of its arms slotted and extending toward the feed-advance rock-shaft alongside said first mentioned slotted arm, a feed-dog, a feed-bar carrying said feed-dog, one or 5 more feed-bar carrying arms on said feed-lift rock-shaft, a feed-advance actuating connection between said lever and said feed-bar, and a feed-adjusting pin adjustably secured to one of said slotted arms and extending into 10 the slot in the other slotted arm.

4. A sewing machine having, in combination, a frame including a standard, a bracket-arm and a cylinder-bed, a main-shaft journaled in said frame in line with and extending 15 into said cylinder-bed, a throat-plate formed with feed-dog slots, a feed-dog, an inverted U-shaped feed-bar, a feed-lift rock-shaft, spaced crank-arms on said rock-shaft pivotally connected to the lower ends of the 20 legs of said feed-bar, a bell-crank lever fulcrumed on said feed-lift rock-shaft, one arm of said bell-crank lever being connected to said feed-bar and the other arm extending across the cylinder-bed, a feed-advancing 25 rock-shaft having a crank-arm extending alongside said other arm of the bell-crank lever, and an adjustable pin-and-slot connection between said last mentioned arms.

5. A sewing machine having a frame including a standard, a bracket-arm and a cylinder-bed, a main-shaft journaled in line with and extending into said cylinder-bed, a reciprocating needle, a looper, a rocking and sliding looper-supporting shaft journaled 35 in and lengthwise of said cylinder-bed below said main-shaft, a four-motion feed-dog, feed-advance and feed-lift rock-shafts journaled within and lengthwise of said cylinder-bed at opposite sides of said main-shaft, operative 40 connections between the main-shaft and looper-supporting shaft for rocking and sliding the latter, the said means for rocking the looper-shaft including an eccentric carried by the main-shaft within the cylinder-bed and an arm connected to the looper-shaft and embracing said eccentric, and operative 45 connections between the main-shaft and said feed-advance and feed-lift rock-shafts, said last mentioned connections including a pair 50 of eccentrics on the main-shaft at opposite ends of said looper-shaft rocking eccentric.

6. A sewing machine having, in combination a frame including a standard, a bracket-arm and a cylinder-bed, a main-shaft journaled in said frame in line with and extending 55 into said cylinder-bed, a throat-plate formed with feed-dog slots, a feed-dog, an inverted U-shaped feed-bar, a feed-lift rock-shaft, spaced crank-arms on said rock-shaft 60 pivotally connected to the lower ends of the legs of said feed-bar, a bell-crank lever fulcrumed on said feed-lift rock-shaft, one arm of said bell-crank lever being connected to said feed-bar and the other arm extending 65 across the cylinder-bed, a feed-advancing

rock-shaft having a crank-arm extending alongside said other arm of the bell-crank lever and means for relatively adjusting the arms of said bell-crank lever angularly to center the feed-dog in the feed-dog slots in 70 the throat-plate.

7. Feeding mechanism for sewing machines comprising, feed-lift and feed-advance rock-shafts, a feed-lifting arm fixed to said feed-lift rock-shaft, a feed-dog, a feed-bar carrying said feed-dog and including an arm rigid with said feed-bar and extending downwardly to and pivotally connected with said feed-lifting arm, a lever fulcrumed coaxially with said feed-lift rock-shaft and connected to impart feed-and-return motions to said feed-bar, and means connected to said feed-advance rock-shaft for vibrating said lever.

In testimony whereof, I have signed my name to this specification.

ANDREW B. CLAYTON.
